INSIDE MICROMETER

Joseph F. Rondinone, Wethersfield, Conn., assignor
or of one-fourth to Winifred C. Rondinone,
Wethersfield, Conn.

Application January 21, 1943, Serial No. 473,087

5 Claims. (Cl. 33—154)

This invention relates to inside micrometers and has for its object to provide a micrometer for measuring inside dimensions accurately and which will be easy to read.

A further object of the invention is to provide an inside micrometer employing a standard type of micrometer mechanism which is very convenient to use.

Further objects of the invention will be more clearly understood from the following description and from the accompanying drawing in which:

Fig. 1 is a plan view of an inside micrometer embodying my invention.

Fig. 2 is a side view thereof.

Fig. 3 is an enlarged rear view of a portion of the device showing the mounting of the swivel connection.

Fig. 4 is a view in central vertical section of the portion shown in Fig. 3.

Fig. 5 is a plan view on an enlarged scale with parts shown in section on line 5—5 of Fig. 2.

As shown in the drawing, my improved inside micrometer may employ a structure similar to inside calipers which may consist of legs 5 and 6 that are pivoted at 7 and have measuring points 8—8.

My invention provides a micrometer construction which is attached to the said legs and consists of a conventional form of a micrometer mechanism having the usual graduated barrel 9 and the corresponding sleeve 10 which operates the slide bar 11 in the well known manner that it is operated in the conventional form of micrometers.

A supporting member 12 is secured to the barrel 9 and swively connected to the leg 6, preferably by means of a screw 14. The other leg 5 of the calipers is swively connected to the slide bar 11 by means of pivots, such as screws 15, which engage a swivel block 16. The end of the spindle 11 is reduced as at 17, extends through the said block 16 and is secured thereto by means of a screw 18 and a washer 19. A spring 20 is provided, between the said block 16 and the shoulder 21 on the spindle 11, and exerts a tension which forces the block 16 against the washer 19.

This construction eliminates lost motion in the connection between the bar 11 and the leg 5 and provides the clearance necessary to permit rotation of the spindle 11 in the block 16.

In the use of my invention, such as in measuring the inside of an opening, the points 8—8 are inserted in the opening and the sleeve 10 is then turned until the said points engage the walls of the opening or the points to be measured.

Contact between said points or walls will be easily felt, through the resistance applied to the turning of the sleeve 10, just as the contact is actually made, for the reason that the spring 20 keeps the leg 5 always in engagement with the end of the spindle 11 and eliminates lost motion, between said leg and the bar, which would otherwise tend to cause error in measuring for close dimensions.

In the construction shown, the graduations on the barrel 9 and the sleeve 10 are spaced according to the movement of the points 8—8 on a line indicated at 22, in this case, the ratio between the movement at the points 8—8 on the line 22 and the movement of the legs on the line 5—5 being two to one. In other words, the points 8—8 will move one-half an inch while the legs will move only one-quarter of an inch at the line 5—5. This will permit the use of a relatively short barrel 9 and sleeve 10 which is an advantage in the manufacture of my invention as well as in the use thereof.

Error between the distances actually moved by the points 8—8 and those indicated by the graduations on the barrel 9 is eliminated and the use of a variably graduated scale is rendered unnecessary by the fact that, in the operation of my improved micrometer, the line 22 and the line 5—5 are always in parallel positions regardless of the distances between the points 8—8 on line 22 and the pivots on line 5. Further, it is to be noted that the member 12 bridges around the leg 5 and that the pivoted block 16 moves between the pivot 14 and the barrel 9. Thus, the pivot for the block 16 retains the micrometer measuring mechanism with its axis always on line 5—5 and parallel to the line indicated at 22; thereby insuring accurate measurements by maintaining a constantly uniform ratio between the distances travelled by the points 8—8 on line 22 and by the pivots on line 5.

While I have shown my invention as applied to a caliper construction, the same may also be applied to various other forms of measuring devices without departing from the scope of my invention as set forth in the appended claims.

I claim:

1. An inside micrometer of the character described comprising a pair of pivoted leg members and a measuring mechanism carried on said members intermediate the ends thereof; said measuring mechanism including a supporting member pivotally connected to the side of one of said members and having a portion extending around the other leg member to the outer side thereof, and standard measuring means carried on said sup-

porting member; said measuring means including a barrel having graduations thereon and mounted on the said portion of the supporting member, a sleeve movable over said barrel, and a spindle movable with said sleeve and swivelly and rotatably connected to the said other leg member to thereby permit direct reading of the graduations on said barrel.

2. An inside micrometer of the character described comprising a pair of pivotally connected leg members having a measuring mechanism mounted thereon intermediate the ends thereof; said measuring mechanism including a supporting member swivelly connected to the side of one of said leg members and having a portion extending around the other leg member to the outer side thereof relative to the first leg member, and standard measuring means carried on the said portion of the supporting member and including a spindle swivelly and rotatably secured to the other leg member to thereby permit direct reading of graduations of said measuring mechanism.

3. An inside micrometer comprising a caliper construction including a pair of pivotally connected leg members and a measuring mechanism; said mechanism including a barrel having a sleeve movable thereover, a frame extending from said barrel and swivelly connected to one of said leg members, a block pivoted to the other leg member, a spindle movable with said sleeve and rotatably connected to said block for securing the said measuring mechanism to said other leg member, anchoring means rotatably securing said spindle to said block, and spring means urging said block into engagement with said anchoring means to thereby prevent lost motion between the said block and spindle.

4. An inside micrometer of the character described including a caliper construction comprising a pair of pivotally connected leg members, a supporting member secured to the side of one of said leg members, a portion of said supporting member extending past the side of the other leg

member and having a bearing portion positioned exteriorly of said caliper construction and adjacent to the other leg member, a measuring barrel mounted on said bearing portion, a measuring sleeve movable over said barrel, a spindle connected to said sleeve and rotatable in said bearing portion and movable along the axis thereof, and means for securing said spindle to the other leg member; said means including a pair of pivoting members threaded to said leg member and projecting into an opening therein, a pivoted member supported between said pivoting members and having an opening therein, a reduced portion on said spindle projecting through said opening in the pivoted member, anchoring means on the end of said spindle and abutting the side of said pivoted member to retain it in position relative to said spindle, and a spring on said reduced portion urging said pivoted member against said anchoring means to prevent lost motion between the said spindle and pivoted member.

5. An inside micrometer comprising a caliper consisting of a pair of pivotally connected legs and a micrometer measuring mechanism connected to the said caliper for operating said legs, said measuring mechanism including a frame extending to one side of said caliper and pivotally connected to the leg member at the opposite side of the caliper and adapted to receive the other leg member for movement between the ends thereof, said frame including a measuring mechanism having a barrel bearing standard graduations thereon, said barrel being carried by said frame, a measuring sleeve movable over said barrel, and a measuring spindle operable with said sleeve and extending through said barrel and pivotally and swivelly connected to the said other leg member whereby the said sleeve will move outwardly over said barrel upon the opening of said caliper and inwardly over said barrel upon the closing of said caliper and thereby permit direct reading of said graduations.

JOSEPH F. RONDINONE.
